US00D996016S

(12) United States Design Patent (10) Patent No.: US D996,016 S
Franklin (45) Date of Patent: * Aug. 22, 2023

(54) FOOTWEAR

(71) Applicant: TBL Licensing LLC, Stratham, NH (US)

(72) Inventor: John Franklin, Andover, MA (US)

(73) Assignee: TBL Licensing LLC, Stratham, NH (US)

() Term: 15 Years

(21) Appl. No.: 29/777,805

(22) Filed: Apr. 8, 2021

(51) LOC (14) Cl. 02-04

(52) U.S. Cl.

USPC D2/953; D2/951; D2/947

(58) Field of Classification Search

(57) CLAIM

The ornamental design for a footwear, as shown and described.

DESCRIPTION

FIG. 1 is a front bottom left perspective view of the footwear, according to my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear bottom right perspective view thereof.

The broken lines of even length depict portions of the footwear that form no part of the claimed design. The broken lines of uneven length are boundary lines that form no part of the claimed design.

1 Claim, 8 Drawing Sheets
